J. KUCZYNSKI,
QUICK ADJUSTABLE WINDOW SHADE HOLDER,
APPLICATION FILED JULY 21, 1920.

Patented Mar. 8, 1921.

2 SHEETS—SHEET 2.

UNITED STATES PATENT OFFICE.

JOSEPH KUCZYNISKI, OF JAMAICA, NEW YORK.

QUICK-ADJUSTABLE WINDOW-SHADE HOLDER.

1,371,033.

Specification of Letters Patent.

Patented Mar. 8, 1921.

Application filed July 21, 1920. Serial No. 397,888.

To all whom it may concern:

Be it known that I, JOSEPH KUCZYNISKI, citizen of Poland, residing at Jamaica, in the county of Queens and State of New

5 York, have invented certain new and useful Improvements in Quick-Adjustable Window-Shade Holders, of which the following is a specification.

The main object of this invention is to 10 provide a curtain or shade holding device which may be readily attached to or removed from any window without the use of screws, rivets, nails, or any other ordinary fastening means or tools.

15 The above and other objects will become apparent in the description below, in which characters of reference refer to like-named parts in the drawings.

Referring briefly to the drawings, Figure 20 1 is a plan view of my device.

Fig. 2 is a side elevational view of the same, with parts broken away.

Fig. 3 is an end elevational view of the same.

25 Fig. 4 is a perspective view of one of the gripping racks.

Fig. 5 is a plan view of a similar device with the gripping racks extended.

Fig. 6 is a side elevational view of the 30 latter, with parts broken away.

Fig. 7 is a perspective view of my device as applied to a window frame.

Fig. 8 is a cross-sectional view on the line 8—8 of Fig. 6.

35 Referring now in detail to the drawings, the numeral 1 represents the frame of my device, having an upper and lower block 3, the frame being held together by bolts 2. A shaft 5 is pivotally supported in said frame, and a pinion 9 is mounted upon said shaft between the sides of said frame. Outside said frame a ratchet wheel 4 is mounted upon said shaft, and a handle 6 extends from the shaft. A horizontal support 14 having a recess 15 for the reception of a curtain-

or shade-holder drum or shaft, extends from the frame 1. A pawl 7 is pivoted to said member 14 and is urged by a spring 8 to engage the ratchet wheel 4.

Within the frame 1, situated one above 50 and the other below the pinion 9, are racks 11 and 10, having pointed ends 12 and 13. These racks are slidably mounted between said gear and the blocks 3, so that upon turning of said gear in one direction the racks 55 will be extended from the frame, and turning the gear in the reverse direction will cause the racks to be retracted into the frame.

The device shown in Figs. 6 and 7 is the 60 same as that in the other figures excepting that it is to be used on the opposite side of the window frame. The extension 14 thereof is provided with a hole 16 instead of the recess 15, as is common in shade holders. 65

In use, one of said devices is placed in the groove 20 on each side of the window, the same being the groove in which the window is slideable. Then the handle 6 is turned so as to extend the racks 10 and 11, whence the 70 ends of said racks are urged into the sides of said grooves, securing the same in a tight grip. Thus the devices may be readily applied to any window, and equally as readily removed. 75

I claim:

A device of the class described comprising a frame, a horizontal support extending from said frame, a gear pivotally mounted in said frame, racks above and below said 80 gear and in mesh therewith, the ends of said racks being pointed, a ratchet wheel rigid with said gear outside said frame, a pawl pivotally attached to said horizontal support and lying in releasable engagement 85 with said ratchet wheel, said device being adapted to be secured between the sides of the vertical grooves of a window frame.

In testimony whereof I affix my signature.

JOSEPH KUCZYNISKI.
